United States Patent Office.

JESSE REYNOLDS, OF PHILADELPHIA, PENNSYLVANIA.

Letters Patent No. 102,866; dated May 10, 1870.

HEATING-DRUM.

The Schedule referred to in these Letters Patent and making part of the same.

To all whom it may concern:

Be it known that I, JESSE REYNOLDS, of the city of Philadelphia, in the State of Pennsylvania, have invented a certain new and useful Improvement on Drums or Radiators, and I do hereby declare that the following is a full, clear, and exact description of the same, reference being had to the accompanying drawing and to the letters and marks thereon, which said drawing forms part of this specification, and represents a drum or radiator constructed under my invention;

Figure 1 thereof being a view of such drum in elevation; and

Figure 2, a view of the interior of the box or head, the bottom-plate of the box being removed, and the view had by looking toward the lower ends of the pipes of the drum.

In both of these figures where like parts are shown, like marks and letters are used to indicate the parts.

This invention is of the character of an "additional improvement" to that on which Letters Patent were granted to Jesse Reynolds and Wm. Steffe, on the 11th day of August, 1868, and, like that invention, relates to that class of drums or radiators which is used in the air-chambers of house-warming heaters or furnaces, more specially intended to increase the surface exposed to the products of combustion and the radiating surface for heating the air.

Like the patented invention here referred to, this improvement, also, is intended to be a permanent fixture in the air-chamber, the several parts thereof being made of heavy iron or plate metal, well riveted or secured together, so as to have perfect joints, through which no commingling can occur of the air to be heated, on the one side, and the products of combustion on the other side, and the lower pipes thereof

to be extended through the brick-work or walls of the heater or furnace, to admit of the cleaning of the interior of the drum or radiator from the outside thereof.

The head or box *a*, of this radiator, has an inlet-pipe, *b*, and an outlet-pipe, *c*, for the entrance and exit of the products of combustion, and plates *d*, *e*, and *f*, for directing such products through the vertical pipes *g*, and horizontal pipes *h*. The number of such directing-plates and their position in the box, will, of course, be due to the number of vertical and horizontal pipes that may be used in making the radiator. By the drawing, four vertical and two horizontal pipes only are shown.

The track taken by the products of combustion entering the box, passing through the pipes, and leaving the box, is indicated by fig. 2 of the drawing; and it will readily be seen that, under this arrangement of pipes and box with directing-plates, the products of combustion may be so directed as to utilize a very great proportion of the heat produced.

For the purpose of having access to the head or box and the horizontal pipes, other pipes may be passed therefrom through the walls or brick-work, so that the box and pipes may easily be cleaned.

Now what I claim as my invention, and desire to secure by Letters Patent, as an improvement in the class of radiators or drums herein referred to, is—

The arrangement of vertical and horizontal pipes with the box or head, and directing-plates, as herein recited.

This specification signed this 28th day of March, 1870.
